The present invention relates to a process and device for avoiding short circuit damage in electrolytic cells.

Nowadays in the field of electrolysis of alkali metal chlorides the trend is to construct larger units for electrolysis, since, as compared with smaller units, they have a number of advantages, for example lower construction costs, better controllability of the total unit, and smaller number of individual parts.

Mercury cells, of all those of horizontal construction, are superior to diaphragm cells. The largest diaphragm cells used in industry are mostly operated at a current intensity of about 30,000 amperes, while mercury cells are frequently operated at 100,000 to 200,000 amperes.

Because of the high current intensity of modern mercury cells in operation with minimum voltage, i.e. smallest electrode distance, and with the use of large anodes, the short circuits occurring between the electrodes, which tend to occur particularly when the current intensity varies considerably or with circulation failures in the cell, for example owing to an electrode fracture, gain more and more importance and are today a more serious problem than in the past. This problem is especially serious in modern units with well designed lowering devices for the anodes in which, in order to minimize power losses, the electrode distance is as small as possible and kept practically constant over the whole period of operation of the cell. The seriousness of this problem is further increased by the fact that short circuits occurring in electrolytic cells operated with very high current intensities may cause considerable damage.

The detrimental Joule's heat occurring between an anode and the cathode as a result of a short circuit could be used, for example by means of a thermo-element (bimetal) measuring the temperature, to cut off electrically or mechanically the current supply to the anode by a control element, but devices of this kind would be very complicated and thus uneconomical and unsuited for industrial use.

It would be likewise too expensive, complicated, and unsatisfactory to use the considerable current increase occurring in a short circuit to actuate a suitable control element via an ampere meter.

Now, we have found a process which avoids short circuit damage in electrolytic cells, especially in horizontal mercury cells used for the electrolysis of alkali metal chlorides, and does not show the above disadvantages. The process of the invention enables electrolytic cells to be safely operated with very high current intensity in a simple and economical manner. The Joule's heat occurring in the anode bar as a result of a short circuit is used for melting an alloy that is fusible at a temperature in the range from about 80° C. to 180° C., preferably 100° C. to 140° C., and, under normal conditions of electrolysis, holds together two metal parts in the form of a soldered joint. By spring power the two metal parts are then automatically separated and the current supply is instantaneously interrupted.

A further object of the present invention is to provide a device for carrying out the above process. The current lead to the anode shaft is provided on the other end with a metal part comprising a plug. The plug is soldered into a recess of a second metal part by means of an alloy, said second metal part being attached to the current supply guides of the electrolytic cells. The Joule's heat occurring between the anode and the cathode as a result of a short circuit melts the alloy before damage can occur. The current lead is connected with the anode support by a spring which is insulated to prevent current from blowing through it.

In the accompanying drawings, FIGURES 1-4 diagrammatically represent by way of example a suitable embodiment of the device of the invention. FIGURE 1 illustrates the whole device and the parts of an electrolytic cell directly connected therewith, and FIGURES 2-4 show, on an enlarged scale, the essential parts of the device. In FIGURES 1-4 numeral 1 is a copper rod, 2 is the current lead connected therewith, 4 is the metal part provided with a plug 3 which is fixed to current lead 2. 5 designates the current supply guides of the electrolytic cell upon which there is fastened metal part 7 with recess 6. Numeral 8 denotes insulators, 9 is the spring fixed between anode support 10 and current lead 2, 11 is a contraction in metal part 7 reducing the cross section. 12 represents the soldered joint between the copper rod and anode shaft 13, 14 is the cover of the electrolytic cell, 15 designates the anode block of graphite directly above the mercury cathode, and 16 is the soldered joint holding together metal parts 4 and 7 and which is melted by the heat accumulation resulting from a short circuit.

FIGURES 3 and 4 show, by way of example, a suitable form of metal parts 7 and 4, on an enlarged scale.

In the device of the invention it is of advantage to join parts 4 and 7 by soldering plug 3 into recess 6 with an alloy having a melting point in the range from 80° C. to 180° C., and preferably 100° C. to 140° C. Especially suitable are alloys of lead, tin, antimony, bismuth and the like. All other metal parts of the anode supply are preferably made of copper.

Current lead 2 is suitably made of copper bands in sandwich form.

In order to better accumulate the Joule's heat produced in a short circuit in the immediate neighbourhood of soldering joint 16, it is advantageous to reduce the cross section of metal part 7 near the soldering joint, for example by a contraction 11.

The function of the device of the invention shown in FIGURES 1-4 is very simple. The Joule's heat occurring in a high current flow short circuit which may damage the electrolytic cell melts at soldering point 16 the metal alloy connecting metal parts 4 and 7, and the current-insulated spring 9, fastened between the current lead 2 and the anode support 10, pulls plug 3 of metal part 4 fixed to the current lead out of recess 6 of metal part 7 and thus interrupts at once automatically the current supply to the anode.

The device of the invention can be placed in series or in shunt into the current lead to the anode.

The quick melting of the soldered joint connecting the two metal parts 4 and 7 is enhanced by the fact that the reduced cross section of plug 3 provides a higher current density at the soldering point so that in the case of a high short circuit current a higher Joule's heat is produced at this point. With a normal current intensity in the cell the voltage loss at the soldering joint is so low that it can be neglected.

In case the copper rod 1 is soldered into graphite shaft 13 (soldering point 12) metal parts 4 and 7 must be soldered by an alloy which has a lower melting point than the alloy used for soldering joint 16. When, for example,

copper rod 1 is soldered into graphite anode shaft 13 with an alloy that melts at about 180° C., an alloy having a melting point of 80° C. to at most 180° C. and preferably of about 120° C. is advantageously used for soldering joint 16.

The alloy connecting metal parts 4 and 7 has a melting point such that the melting time on the occurrence of a short circuit is as short as possible, depending on the local conditions. This is particularly favored by the increase of the current density due to the reduction in size of plug 3 and recess 6.

The advantage of the safety fuse of the present invention resides in the fact that the individual parts are very simple and readily available, and that plug 3 can be soldered into recess 6 very quickly and easily. After having eliminated the cause of the short circuit, the individual parts are ready for re-use, and plug 3 of metal part 4 is again soldered with the alloy concerned into recess 6. The shape of parts 7 and 4 shown in FIGURES 3 and 4 provides an especially good soldered joint. Recess 6 of part 7 is filled with solder and plug 3 of part 4 is then introduced into the filled recess. After cooling and solidifying of the solder, and after having fastened current lead 2 to metal part 4, the safety fuse is again ready for use.

By the rapid interchange of the main parts of the device of the invention with a stock of ready soldered reserve parts, short circuit damage can be avoided with reliability in modern large electrolytic cells.

We claim:

1. In an electrolytic cell having an anode and a source of electric current for said anode, a reusable fuse for making a reformable connection of said source to said anode and automatically disconnecting said source from said anode when there is a short circuit which comprises a flexible current lead connected to the anode at one end and having at its other end a conducting member with a plug portion, a second conducting member connected to the source of electrical energy and having a recess engageable by said plug, said plug being retained in said recess for conducting an electrical current of preselected maximum intensity from said source to said anode by an alloy solder having a preselected melting point, said alloy solder comprising the sole means physically securing said receiving member to said plug member, at least one of said plug portion and said second conducting member having a cross-sectional area adjacent said solder substantially less than the minimum cross-sectional area of said flexible current lead, and spring means for withdrawing the plug from the recess upon melting of the alloy solder.

2. A device as claimed in claim 1, wherein the alloy used for soldering the plug into the recess of the metal part has a melting point in the range from about 80° C. to 180° C.

3. A device as claimed in claim 1, wherein the current lead to the copper rod is composed of copper bands in sandwich form.

4. A device as claimed in claim 1, wherein for obtaining a better heat accumulation the second metal part has a reduced cross section near the soldering point.

5. In an electrolytic cell having a pair of electrodes adapted to be energized by high-current electrical supply means, reusable fuse means for providing a reformable conductive connection between one of said electrodes and said supply means and automatically breaking said connection when a short-circuit is created between said electrodes, said fuse means comprising, in combination, a conductor conductively connected to said one electrode and having a plug member at one end, a conductive receiving member conductively connected to said supply means and having a recess adapted to receive said plug member, and a quantity of alloy solder in said recess securing said plug member to said receiving member, said alloy solder comprising the sole means physically securing said receiving member to said plug member, at least one of said plug member and said receiving member having a cross-sectional area adjacent said quantity of solder substantially less than the minimum cross-sectional area of said conductor so as to accelerate the heating and melting of said solder and free said members from one another when short-circuit currents flow through said one member, said cross-sectional area of said one member being sufficient to prevent melting of said solder when the current flow through said one member is less than a predetermined maximum value.

6. Apparatus as in claim 5 including means biasing said plug member away from said receiving member so as to automatically separate said members when said solder melts.
